BLOCK SIGNAL AND TRAIN CONTROL SYSTEM FOR ELECTRIC RAILROADS, ETC.

Frederick C. Kinney, Evanston, Ill.

Application October 12, 1938, Serial No. 234,545

16 Claims. (Cl. 246—85)

This invention relates to circuit controls, signal devices, automatic speed regulators, etc., to railroads, and toy railroads, and more particularly to an automatic block signal and train control therefor. This invention obviously has many other uses.

The primary object of the invention is to generally improve block signal systems for railroads, and also safety train control systems. These systems may be advantageously combined in order to signal and/or control one or more toy trains, separately or together. The invention is described herein, for the purpose of illustration, in connection with a toy railroad, and one object 15 of the invention is to improve toy railroads.

Block signal systems and safety train control systems are well known in connection with real railroads, the track of which is ordinarily divided into a series of successive blocks having signals 20 associated therewith. In a real railroad the service rails are mounted on wooden ties or sleepers and are therefore insulated from one another and are available to signal the presence of a train in the block, said train closing a signal 25 circuit between the two service rails. Similar systems have been proposed for toy railroads, but are inconvenient and expensive and are therefore not commonly used in connection with ordinary toy train sets sold under commercial production and volume sale conditions. Conventional toy tracks have the rails mounted on metallic ties, and the service rails are both grounded. It would be inconvenient and expensive to insulate the service rails from one another throughout 30 the track system, and any signal system based on the use of such tracks would be inapplicable to existing toy train sets already in use.

One important object of the present invention resides in the provision of a signal system which 35 will be applicable to conventional toy tracks having grounded service rails. In accordance with the present system, contactors are used, which may be made in a variety of forms, and in the present illustration, comprise short contact strips used to mark the passage of a train out of a block, and these strips may be placed at any desired 40 points along the track. The system is therefore applicable to existing train sets and is very flexible in meeting varied track layout conditions. However, the contact strips provide only a momentary signalling current, whereas the signal condition and train control condition should be maintained until another block is reached, and it is a further object of the present invention to 45 overcome this difficulty.

Other objects of the present invention center about the train control system, and are to provide a slow speed or "caution" condition, as well as the "stop" and full speed conditions; to provide, when desired, a reversing of a train having 5 a remote control reversing mechanism; to provide a small holding potential instead of complete deenergization or open-circuiting of the control section for the "stop" condition in order to prevent undesired operation of the remote 10 control reversing mechanism of trains having such mechanism; to utilize a single resistor to provide both the holding potential and the slow speed potential, depending on the condition of the signal; and finally, to make the slow speed potential 15 a readily adjustable or variable potential so that it may be set to accommodate varied conditions such as the use of a long or heavily loaded train in contradistinction to a short or lightly loaded train.

Still another object is to arrange the system for manual control at a remote point. This is readily done by the use of push-buttons because a momentary energization or total deenergization 20 for remote control reversing mechanisms is adequate. Still another object is to provide a signal and control mechanism which is compact, 25 simple, and inexpensive to manufacture.

To the accomplishment of the foregoing and other objects which will hereinafter appear, my 30 invention, for the present illustration, consists in the block signal and train control elements and their relation one to the other as hereinafter are more particularly described in the specification and sought to be defined in the claims. The 35 specification is accompanied by a drawing, in which:

Fig. 1 is a partially sectioned front elevation of a signal embodying my invention;

Fig. 2 is a partially sectioned side elevation of 40 the same;

Fig. 3 is a horizontal section taken in the plane of the line 3—3 of Fig. 2 and shows the relay mechanism in plan;

Fig. 4 is a fragmentary section taken in the 45 plane of the line 4—4 of Fig. 3;

Fig. 5 is a wiring diagram explanatory of the invention; and

Fig. 6 is explanatory of the operation of certain contact strips used with the invention.

Referring to the drawing, the block signal comprises a generally upright support carrying three signal lamps 12, 14, and 16. These are appropriately colored, and in accordance with conventional practice are colored red, yellow and green,

- respectively corresponding to "stop" or "danger," "go slow" or "caution," and "go fast" or "clear."
- The support may be made in a variety of forms, and in the present case comprises an enlarged bottom portion 18, an intermediate portion 20 thereabove, and a post 22 surmounting the intermediate portion 20. The bottom portion 18 carries a selector mechanism for selecting which of the signal lamps is to be energized. In general, the selector mechanism comprises a movable element and a group of stationary contacts any one of which may be engaged by movement of the movable element, and said movable element may therefore be referred to as a selector.
- In the specific form here shown, the movable element or selector is a three-armed armature 24, said armature being made of magnetic material and being pivotally mounted for universal tilting or rocker movement. For this purpose, the armature is struck upwardly at 26 to form a bearing. The armature may be held on this bearing, mounted integrally together in the manner of a universal joint, preventing detachment, yet permitting free tilting or rocker movement of the armature within the stationary contacts which also serve to guide direction of such movement. This construction may be made in a variety of forms. For the present case, this bearing is received on the pointed upper end of a suitable pin-like support or fulcrum bearing 28. The armature is held on its fulcrum not only gravitationally, but also by means of a resilient strip 30, the upper end of which bears against the preferably slightly rounded tip of the bearing protuberance 26, and the lower end of which is secured to the base 32 of the signal, as by means of screw 34. It will be understood that the intermediate part of the spring strip 30 is so bent as to safely clear the armature 24 and thus avoid interference with its tilting movement. The bearing 28 may be used as a contact strip to the armature 24, but as will later appear, the strip 30 is preferably further used as a contact strip to convey current to armature 24.
- The complete selector or triple relay mechanism further includes three magnets 36, 38, and 40. These magnets are disposed with their axes parallel and are located in triangular formation, each magnet being beneath one of the arms of armature 24. Energization of one of the magnets causes the arm thereabove to be attracted downwardly, and this at the same time elevates the other two arms away from the other magnets.
- A spring contact is associated with each of the magnets for engagement by the selector. Referring to Fig. 5, the selector is schematically indicated by the triangular element 24, and the stationary contacts last referred to are indicated at 42, 44, and 46, these contacts being respectively connected to the lamps 12, 14, and 16. The opposite terminals of the lamps are grounded, as is indicated at 48, preferably by connecting the same to one of the service rails 50 of the track system, such connection being indicated at 52. The service rails 50 are electrically joined by metal cross-ties of the conventional toy track. The conventional insulated third rail of the track system is indicated at 54, and this is connected to the armature or selector 24, as is indicated by the conductors 56 and 58. It will be understood that conductor 58 leads to the spring strip 30 previously referred to as bearing against the top of the armature.
- It will be appreciated that with this arrangement, movement of the selector into engagement with any of the contacts 42, 44, or 46 causes energization and lighting of the respective signal lamps 12, 14, or 16. It will also be understood that when one lamp is lighted, the others are extinguished, this resulting inherently from the nature of the selector. It is also clear that the selection of the signal depends upon the energization of the magnets 36, 38, and 40, and the manner in which this is done will be explained with further reference to Fig. 5.

The signal system includes a series of short contact strips 62, 64, and 66, the strip 62 being located at the signal, the strip 64 being spaced therefrom by a substantial amount at least equal to the length of the train of cars C, and preferably greater, while the strip 66 is spaced still further along the track in the direction of operation of the train of cars C. The track is energized in the usual fashion from any suitable source of power, as, for example, the transformer T, the leads 68 and 70 therefrom being respectively connected to the metal cross-tie joined service rails 50 and the third rail 54 of the track. The contact strips 62, 64, and 66 are so located as to be engaged by a part of the passing cars C, preferably the wheels of the same, as is best shown in Fig. 6, thus grounding the contact strips by connecting the same to the service rails 50 and cross tie 51 through the medium of the car wheels 53. The contact strips are connected to the operating magnets of the triple relay mechanism, and more specifically, the local or "red" strip 62 is connected to the "red" magnet 36, producing energization of the "red" magnet, drawing armature 24 into contact with lead 42, thus energizing the red lamp; the "yellow" strip 64 is connected to the "yellow" magnet 38, producing energization of the yellow lamp, while the distant or "green" strip 66 is connected to the "green" magnet 40, producing energization of the green lamp. The opposite terminals of the magnet coils 36, 38, and 40 are connected in common to the third rail 54 as by means of the conductor 72 and conductor 56.

It will thus be seen that as the train C reaches and passes the "red" strip 62, the red lamp will be lighted. This lamp should remain lighted until the train reaches the next contact strip 64. Inasmuch as the engagement of the wheels with the contact strip is only intermittent, and inasmuch as the spacing between the contact strips, i. e., the length of the simulated "blocks" of the track system may be much greater than the length of the train, it is necessary that the selector remain in selected position until changed by energization of another magnet. In other words, the relay action should be of the "stick" type. This result is accomplished in the present case by the provision of spring fingers which frictionally engage and hold the armature 24 against movement until another magnet is energized. Specifically, referring to Fig. 2, it will be seen that there are spring fingers 42 and 82 on opposite sides of magnet 36, said fingers engaging the depressed arm of the selector 24. The grip of the spring fingers on the armature is sufficient to hold the armature in place but insufficient to prevent the armature from tilting to a new position upon energization of one of the other magnets. Similarly, each magnet is provided with a pair of spring fingers, the magnet 38 having the fingers 44 and 84, and the magnet 40 having the fingers 46 and 86.

In this way, the red lamp remains lighted until the train reaches the "yellow" strip, whereupon the yellow lamp is lighted and remains lighted until the train reaches the "green" strip, whereupon the green lamp is lighted and remains lighted until the same or another train again reaches the "red" strip at the signal.

So far I have described the invention as a signal system, but the invention preferably also includes train control mechanism for automatically controlling the operation of two or more trains proceeding on the same track, acting to prevent them from touching, or colliding, the controlling mechanism of the signal being actuated automatically by the train ahead so as to control or regulate speed or stoppage of the following or approaching train. The controlling mechanism also is designated so as to be actuated by manual remote control for controlling movement of a single train in accordance with signal light showing as determined by operation of controlling mechanism automatically by another train, or manually. For purpose of illustration, the locomotive and cars C represent the "following train" and its automatic control by the train ahead or its manual remote control, in either case in proper response to the signal indications. Referring to Fig. 5, a section of third rail 54 is insulated from the remainder of the third rail as by removing the connecting pins of the sections, say, at the points 90 and 92. The resulting control section 94 is preferably made equal to the stopping distance of the train when the power supply thereto is cut off, thus insuring stoppage of the train within the control section. This control section is preferably located immediately ahead of the signal and is controlled by the signal. The "red" contact strip 62 is preferably located at the signal and therefore at one end of the control section 94. The system is provided with a voltage reducing resistor 96 adapted to be inserted in the current supply to the isolated third rail section 94. The resistance is preferably tapped by a movable tap 98, and the part 100 of the resistor at the left of tap 98 acts as a voltage reducing resistor to produce slow speed operation of the train when facing a yellow or "caution" signal. In Fig. 5, it will be seen that the third rail of the control section 94 is connected by means of a conductor 102 to one end of resistor 100, and that the tap 98 is connected by means of a conductor 104 to the contact strip 84, corresponding to the yellow or "caution" signal. Obviously, when the yellow signal is lighted, the control section is energized from the main third rail 54 through resistor 100, thus producing slow speed operation of the train. It will also be seen that the end of resistor 100 is connected by means of a conductor 106 to the contact 86 associated with the "green" contact 46. It will thus be clear that when the green lamp is lighted the resistor 100 is short-circuited or cut out of circuit, and the main third rail 54 is connected directly to the control section 94. When the red lamp is lighted, the train is to be stopped, and for this purpose it is merely necessary to open-circuit the current supply to the control section. However, inasmuch as many toy trains are equipped with remote control reversing mechanism, which mechanism functions in response to opening of the supply circuit, yet may not respond to a small holding current which is inadequate, however, to drive the train, I prefer to supply such a small holding current to the

control section. For this purpose, the complete resistor 96 is employed, and it is appropriately dimensioned for that purpose. The "red" contact 42 has associated with it a contact 82 which is connected to the end of resistor 96 by means of a conductor 108. It will thus be clear that when the red lamp is lighted, the control section is substantially deenergized but is supplied with a small holding potential. Either zero potential or a small holding potential may be generically referred to as a "no speed" potential.

To prevent undesired reversal of the train, it is important that there be no interruption of current during the changeover from one energization to another. This may be accomplished by making the spring fingers sufficient in length so that the selector engages the approaching fingers before leaving the departing fingers. Another way to accomplish the desired result is to connect the holding resistor 96 permanently in circuit, as by means of the conductor 110 extending between the points 112 and 114 in Fig. 5. The use of conductor 110 makes it unnecessary to employ the contact 82, but this contact is preferably retained for mechanical reasons inasmuch as it provides the desired "stick" action on the selector.

The mechanical arrangement of resistor 96 and of the variable tap 98 is shown in Figs. 1 and 2. Arm 98 is insulatedly pivoted at 116, as by making the wall 118 out of insulation material. The lower end of arm 98 is bent outwardly to form a handle 120 which passes through an arcuate slot 122 cut through the wall 118. The resistance winding 96 is carried on an insulation bar 124 which is secured between two of the side walls of the intermediate part of the signal.

The signal lamps may be of conventional type and threadedly received in appropriate sockets 126, the main portion of which may be secured to and grounded on the signal body, and the insulated center terminal 128 of which may be connected through conductors extending downwardly through post 22 to the appropriate contact arms of the selector mechanism.

Remote control of the system is readily provided. This may be done by the use of ordinary spring biased push-buttons because only a momentary energization of the magnets is needed. Thus, reverting to Fig. 5, I provide a remote panel carrying the three push-buttons marked R, Y, and G, and corresponding to the red, yellow and green signals respectively. One terminal of the "red" button is connected through lead 130 to magnet coil 36 or/and the "red" strip 62. One terminal or button Y is connected through lead 132 to the "yellow" magnet 38 or/and the "yellow" contact strip 64. The third button G is connected through lead 134 to the "green" magnet 40 or/and the "green" contact strip 66. The opposite terminals of the buttons are connected together by means of conductor 136 and to ground 138. Ground is preferably obtained by means of a fourth conductor 140 leading back to the signal mechanism and to ground 48 and service rails 50. Thus, the push-button panel is connected to the signal by a four-wire flexible cable of any desired length. By pushing any one of the buttons, the corresponding lamp is lighted and the corresponding train control is exercised. Thus, a train may be stopped at the signal by pressing the "red" button, even though the track is clear and the signal would normally be "green" were it not for the manual intervention.

If desired, the push-button panel may be pro-

vided with a fourth push-button acting as a circuit interrupter button for producing reversing of the train. In the drawing, this button is marked "B". The button is so arranged that 5 the contacts are normally closed. When this fourth button B is used, it is connected by additional leads 150 and 152, the lead 150 being connected to the end of resistor 100, and the lead 152 being connected to the control section 94, or, as 10 here shown, to the conductor 102. At this time, the section of conductor 158 shown between the points 154 and 156 is, of course, removed or broken into by leads 150, 152 so that the current supplied to the control section 94 runs through 15 the normally closed contacts of push-button B. When the push-button is depressed, it momentarily interrupts all current flow to the control section, thus reversing a train of the type having remote control reversing means, provided, of course, that the train is at that time in the 20 control section.

It is believed that the construction and operation, as well as the many advantages of my improved signal and train control system, will be 25 apparent from the foregoing detailed description thereof. It will be understood that if the triangular relay is used for the signal lamps alone, the two spring fingers at each arm of the relay may be in series in a circuit to each lamp, and 30 it would then be unnecessary to conduct current supply through the armature of the relay. Similarly, if the triangular relay is used for train control purposes alone, the two spring fingers may be used in series for the circuits associated 35 with the speed control resistor. However, when the relay is used for both signal and train control purposes, as here disclosed, it is convenient and preferable to supply current to the armature in order that one set of spring fingers may 40 be used for signal purposes while the other is used for train control purposes. Even this, however, is not essential, as three contacts may be provided at each magnet instead of two, and I have made a signal and control device of this character using three spring fingers at each magnet. It will therefore be apparent that while I have shown and described my invention in a preferred 45 form, many changes and modifications may be made in the structure disclosed without departing from the spirit of the invention defined in the following claims. In the claims, the term "no speed potential" is intended to include the case of true zero potential or open circuit, as well as the slight holding potential which is provided 50 when dealing with certain types of remote control trains.

I claim:

1. A train control device for an electrically 60 operated railroad including service rails and a power rail with an insulated control section, said device comprising a movably mounted selector, contacts arranged for selective contact by said selector, means to apply a potential to the insulated control section, a resistor for controlling 65 the potential applied to the insulated control section, the contacts being so connected with said control section and said resistor as to include none, some, or all of the resistance in order to apply full speed, slow speed, or no speed potentials to the control section, means for causing said selector to engage any one of the contacts at a 70 time, the remaining contacts becoming or remaining disengaged, control circuits for the said selector operating means including contactors 75 adapted to be applied in close proximity to the

track at spaced points along the track for engagement by a train part, and means for maintaining the selector in engagement with a contact until moved to another position.

2. A train control device for an electrically 5 operated railroad including service rails and a power rail with an insulated control section, said device comprising a movably mounted selector, means connecting the selector to the power rail, contacts arranged for selective engagement by 10 said selector, means to apply a potential to the insulated control section, a resistor for controlling the potential applied to the insulated control section, means for causing said selector to engage any one of the contacts, the remaining 15 contacts becoming or remaining disengaged, control circuits for the said selector operating means including contactors adapted to be applied in close proximity to the track at spaced points along the track for engagement by a train part, 20 and means for maintaining the selector in engagement with a contact until moved to another position.

3. A block signal and train control device for an electrically operated railroad including service 25 rails and a power rail with an insulated control section, said signal comprising differently colored signal lamps, a movably mounted selector, means connecting the selector to the power rail, pairs of contacts arranged for selective contact by said 30 selector, one contact of each pair being connected to each of the signal lamps respectively, the opposite terminals of the signal lamps being connected in common to the service rails, the other contact of each pair being related to said control section in such manner as to energize or substantially deenergize the control section, means for causing said selector to engage one or another pair of the contacts, the arrangement being such that the remaining pairs of contacts remain or become disengaged, control circuits for the said selector operating means including contactors adapted to be applied in close proximity to the track at spaced points along the track for engagement by a train part, and means for maintaining the selector in engagement with one pair of contacts until moved to another. 35

4. A block signal and train control device for an electrically operated railroad including service rails and a power rail with an insulated control 50 section, said signal comprising three differently colored signal lamps, a movably mounted selector, means connecting the selector to the power rail, pairs of contacts arranged for selective contact by said selector, one contact of each pair being connected to each of the signal lamps respectively, the other contact of each pair being related to said control section in such manner as to energize or substantially deenergize the control section, momentarily energizable means for causing said selector to engage one or another pair of the contacts, the arrangement being such that the remaining pairs of contacts remain or become disengaged, control circuits for the momentarily energizable means including contactors adapted to be applied in close proximity to the track at spaced points along the track for engagement by a train part, and means for maintaining the selector in engagement with one pair of contacts until moved to another. 55

5. A block signal and train control device for an electrically operated railroad including service rails and a power rail with an insulated control section, said signal comprising three differently colored signal lamps, a movably mounted selector, means connecting the selector to the 60

- power rail, pairs of contacts arranged for selective contact by said selector, one contact of each pair being connected to each of the signal lamps respectively, the opposite terminals of the signal lamps being connected to ground or to the service rails, a resistor for controlling the potential applied to the insulated control section, the other contacts of said pairs of contacts being connected with said control section and said resistor in such manner as to include none, some, or all of the resistance in order to apply full speed, slow speed, or no speed potentials to the control section, means for causing said selector to engage any one of the pairs of contacts, the arrangement being such that the remaining pairs of contacts remain or become disengaged, and control circuits for the said selector operating means, including contactors adapted to be applied in close proximity to the track at spaced points along the track for engagement by a train part.
6. A block signal and train control device for an electrically operated railroad including service rails and a power rail with an insulated control section, said signal comprising differently colored signal lamps, a movably mounted selector, means connecting the selector to the power rail, three pairs of contacts arranged for selective contact by said selector, one contact of each pair being connected to each of the signal lamps respectively, the opposite terminals of the signal lamps being connected to ground or the service rails, a resistor for controlling the potential applied to the insulated control section, the other contacts of said pairs of contacts being associated with said resistor, one of said contacts being connected to one end of the resistor and to the control section, another of said contacts being variably connected to the aforesaid resistor by means of a manually adjustable contact arm, the third contact being connected to the opposite end of the resistor, means for causing said selector to engage any one of the pairs of contacts, the arrangement being such that the remaining pairs of contacts remain or become disengaged, control circuits for said selector including contactors adapted to be applied in close proximity to the track at spaced points along the track for engagement by a train part, and means for maintaining the selector in engagement with one control pair until moved to another.
7. A train control system for a railroad comprising a conventional track having grounded service rails and a power rail insulated from said service rails, a control section of said power rail being insulated from the remainder of the power rail, means to apply a potential to the insulated control section, contactors in close proximity with the track at spaced points along the track for engagement by a train part, there being a "stop" contactor at the signal, a "caution" contactor spaced from the "stop" contactor, and a "go" contactor still more remote from the "stop" contactor, a three-position selector, train control contacts mounted for selective engagement by the selector, a resistor, the contacts being so connected with the resistor and control section as to include none, some, or all of the resistance in order to supply said insulated section with a no speed potential, a moderate slow speed potential or full track potential corresponding to "stop," "caution," and "go," and circuit means connected to said contactors for causing movement of said selector.
8. A train control system for a railroad comprising a conventional track having grounded service rails and a power rail insulated from said service rails, a control section of said power rail being insulated from the remainder of the power rail, means to apply a potential to the insulated control section, contactors in close proximity with the track at spaced points along the track for engagement by a train part, there being a "stop" contactor at the signal, a "caution" contactor spaced from the "stop" contactor, and a "go" contactor still more remote from the "stop" contactor, a three-position selector, train control contacts mounted for selective engagement by the selector, a resistor, an adjustable tap movable between the ends of said resistor, said resistor being connected in series with the supply conductor leading to the control section, the train control contacts being so connected as to short-circuit the tapped portion or all of the resistor, whereby said insulated section is supplied with a small holding potential, a moderate slow speed potential or full track potential corresponding to "stop," "caution," and "go," and three magnets responsive to engagement of said contactors for causing movement of said selector.
9. A block signal and train control system for a railroad comprising a conventional track having grounded service rails and a power rail insulated from said service rails, a control section of said power rail being insulated from the remainder of the power rail, means to apply a potential to the insulated control section, a block signal, red, yellow and green lamps on said signal, contactors in close proximity with the track at spaced points along the track for engagement by a train part, there being a "red" contactor at the signal, a "yellow" contactor spaced from the "red" contactor, and a "green" contactor still more remote from the "red" contactor, a three-position selector movably mounted in said signal, signal and train control contacts mounted in said signal for selective engagement by the selector, signal contacts respectively connected to the red, yellow and green lamps, a resistor in said signal, other train control contacts so connected to said resistor and insulated control section as to include none, some, or all of the resistance in order to supply said insulated section with a no speed potential, a moderate slow speed potential, or full track potential corresponding to the red, yellow and green lamps, and circuit means connected to said contactors for causing movement of said selector.
10. A block signal and train control system for a railroad comprising a conventional track having grounded service rails and a power rail insulated from said service rails, a control section of said power rail being insulated from the remainder of the power rail, means to apply a potential to the insulated control section, a block signal, red, yellow and green lamps on said signal, contactors in close proximity with the track at spaced points along the track for engagement by a train part, a three-position selector movably mounted in said signal, signal and train control contacts mounted in said signal for selective engagement by the selector, three of said contacts being signal contacts and being respectively connected to the red, yellow and green lamps, a resistor in said signal, the other stationary contacts being train control contacts so connected to said resistor and insulated control section as to include none, some, or all of the resistance in order to supply said insulated section with a no speed potential, a moderate slow speed potential or full track potential corresponding to the red,

yellow and green lamps, means for causing movement of said selector, and remote push-button switches, one of said selector operating means being connected to each of the aforesaid contactors for automatic operation, and also to each of the aforesaid push-button switches for remote manual control.

11. A block signal and train control system for a railroad comprising a conventional track having grounded service rails and a power rail insulated from said service rails, a control section of said power rail being insulated from the remainder of the power rail, a supply conductor leading to the control section to energize the same, a block signal disposed near the end of the control section, red, yellow and green lamps on said signal, contact strips in close proximity with the track at spaced points along the track for engagement by a train part, there being a "red" strip at the signal, a "yellow" strip spaced from the "red" strip, and a "green" strip still more remote from the "red" strip, a three-position selector movably mounted in said signal, signal and train control contacts mounted in said signal for selective engagement by the selector, three of said contacts being signal contacts and being respectively connected to the red, yellow and green lamps, a resistor in said signal, an adjustable tap movable between the ends of said resistor, said resistor being connected in series with the supply conductor leading to the control section, the other contacts being train control contacts so connected as to short circuit the tapped portion or all of the resistor, whereby said insulated section is supplied with a small holding potential, a moderate slow speed potential or full track potential corresponding to the red, yellow and green lamps, and three magnets for causing movement of said selector, one of said magnets being connected to each of the aforesaid contact strips, the selector and contact arrangement being such that when the selector is moved by one of the magnets into engagement with certain contacts it is moved or remains out of engagement with the other contacts.

12. A train control device for an electrically operated railroad including service rails and a power rail having an insulated control section, means to apply a potential to the insulated control section, a three-armed armature mounted for universal tilting movement, means for selectively moving the arms of said armature into cooperation with corresponding multiple contacts, said contacts being shaped for lightly frictionally receiving and holding an arm of the armature when said arm is actuated by said armature moving means, the arrangement being such that the other two arms are then lifted away from or remain away from the other contacts, a resistor, the contacts being connected with said resistor and said control section in such a manner as to supply a no speed potential, a low speed potential, or full potential to the control section.

13. A block signal and train control device for an electrically operated railroad including service rails and a power rail having an insulated control section, means to apply a potential to the insulated control section, said signal comprising three signal lamps, a three-armed armature mounted for universal tilting movement, means for selectively moving the arms of the armature, a pair of contacts for engagement with each arm of the armature, said contacts being shaped for lightly frictionally receiving and holding an arm of the armature therebetween when

said arm is actuated by said armature moving means, the arrangement being such that the other two arms are then lifted away from or remain away from the other contact springs, one contact of each pair being connected to each of the aforesaid signal lamps, a resistor, the other contacts of each pair being connected with said resistor and said control section in such a manner as to supply a no speed potential, a low speed potential, or full potential to the control section, and push-buttons for manual remote control of said signal lights simultaneously with proper corresponding train control.

14. A block signal system for a railroad, said system comprising a conventional track having grounded service rails, and a power rail insulated from said service rails, a block signal, three differently colored signal lamps, contact strips in close proximity with the track at spaced points along the track for engagement by a train part, there being a "red" strip at the signal, a "yellow" strip spaced from the "red" strip, and a "green" strip still more remote from the "red" strip, a three-armed armature pivotally mounted for universal rocker movement, magnetic means moving said armature, said magnetic means being connected to said contact strips, thin spring contacts for engaging and lightly holding an arm of the armature when attracted by the magnetic means, said contacts being connected to the red, yellow and green lamps respectively, and a suitable return circuit for said lamps.

15. A train control system for a railroad, said system comprising a conventional track having grounded service rails, and a power rail insulated from said service rails, a control section of said power rail being insulated from the remainder of the power rail, means to apply a potential to the insulated control section, contact strips in close proximity with the track at spaced points along the track for engagement by a train part, there being a "red" strip, a "yellow" strip spaced from the "red" strip, and a "green" strip still more remote from the "red" strip, a three-armed armature pivotally mounted for universal tilting movement, three magnets arranged in triangular formation for cooperation with the armature, said magnets being connected to said contact strips, a return circuit for said magnets, thin spring contact fingers at the magnets shaped for lightly frictionally engaging and holding an arm of the armature when attracted by the magnet, a resistor, the contact fingers being so connected with said resistor and said control section as to supply the control section with a no speed potential, a slow speed potential, or full track potential.

16. A block signal and train control system for a railroad, said system comprising a conventional track having grounded service rails, and a power rail insulated from said service rails, a control section of said power rail being insulated from the remainder of the power rail, means to apply a potential to the insulated control section, a block signal disposed near the end of the control section, red, yellow and green lamps on said signal, contact strips in close proximity with the track at spaced points along the track for engagement by a train part, there being a "red" strip at the signal, a "yellow" strip spaced from the "red" strip, and a "green" strip still more remote from the "red" strip, a three-armed armature pivotally mounted for universal tilting movement, three magnets arranged in triangular formation for cooperation with the armature,

5 said magnets being connected to said contact strips, a return circuit for said magnets, pairs of thin spring contacts at each magnet for lightly engaging and holding therebetween an arm of the armature when attracted by the magnet, one contact of each pair being connected to the red, yellow and green lamps respectively, a resistor,

a suitable return circuit for said lamps, the other contact fingers being so connected with said resistor and said control section as to supply the control section with a no speed potential, a slow speed potential, or full track potential, corresponding to the red, yellow and green lamps. 5

FREDERICK C. KINNEY.
